DESIGN FOR A GOLF PUTTER HEAD

John Bernardi, Jamaica Plain, Mass.

Application July 19, 1934, Serial No. 52,631

Term of patent 7 years

To all whom it may concern:

Be it known that I, John Bernardi, a citizen of the United States, residing at Jamaica Plain, in the county of Suffolk, State of Massachusetts, have invented a new, original, and ornamental Design for Golf Putter Head, of which the following is a specification, reference being had to the accompanying drawing, forming part thereof, and in which:

Fig. 1 is a view in perspective of the putter head showing my new design;

Fig. 2 is a view looking toward the putter head

with the flat inner face of the shank in vertical position;

Fig. 3 is a view looking down on the top of the putter head with the flat top face of the body of the head in horizontal position; and,

Fig. 4 is a section taken on the line 4—4 of Fig. 3.

I claim:

The ornamental design for a golf putter head as shown.

JOHN BERNARDI.
